UNITED STATES PATENT OFFICE.

WILLIAM FRANCIS RYAN, OF FLORENCE, MASSACHUSETTS.

STOP COCK.

Application filed December 24, 1924. Serial No. 757,838.

To all whom it may concern:

Be it known that I, WILLIAM F. RYAN, a citizen of the United States, residing at Florence, in the county of Hampshire and 5 State of Massachusetts, have invented certain new and useful Improvements in Stop Cocks, of which the following is a specification, reference being had to the accompanying drawings.

10 This invention relates to improvements in stop cocks and more particularly to a stop cock, the plug of which is so constructed as to eliminate excessive wear.

An important object of the invention is to 15 provide a stop cock, a portion of the plug of which remains stationary and a second portion of which rotates, one of said portions being provided with a seat which is removable and renewable so that the life of 20 the cock may be extended.

A further object of the invention is to produce a device of this character in which the plug is so constructed that turning of the same is rendered a very easy operation 25 as compared with the ordinary type of stop cock where the plug fits tightly against the walls of the chamber.

These and other objects I attain by the 30 construction shown in the accompanying drawings, wherein for the purpose of illustration is shown a preferred embodiment of my invention and wherein:—

Figure 1 is a perspective view of a stop cock constructed in accordance with my invention, the cap of the valve body being removed to show the limit mechanism employed;

Figure 2 is a vertical sectional view 35 through the cock;

Figure 3 is a sectional view taken through the cock at the channel 28;

Figure 4 is a perspective view of the upper or body section of the rotating part;

Figure 5 is a perspective view of the seating section of the rotating part;

Figure 6 is a perspective view of the stationary part; and

Figure 7 is a combined perspective view 50 showing the arrangement of the seating section and stationary part where a plurality of outlets are desired.

Referring now more particularly to the drawings, the numeral 10 generally indicates a body of a stop cock having a vertical 55 tapered bore 11 terminating at its lower end

in a threaded bore 12 and having an inlet 13, and an outlet 14 communicating with the tapered portion of the bore adjacent the lower end thereof. The upper end of the exterior of the body is threaded, as at 15, 60 for the reception of a cap 16, this threaded portion having formed therein a notch 17 extending circumferentially through a distance equal to that through which the valve plug, hereinafter referred to, rotates. The 65 cap 16 has a central opening 18.

The valve plug is formed in two sections 19 and 20, the section 19 being hereinafter referred to as the stationary section while the section 20 will be referred to as the 70 rotatable section. The stationary section has at its lower end a threaded portion, the threads of which engage the threaded portion 12 of the bore of the valve body and by this means is held in stationary position. The stationary section has inlet and outlet ports 21 and 22 aligning with the ports of the inlet 13 and outlet 14 and has vertical bores 23, 24, communicating with the ports 21, 22 and opening through the 75 upper end of the stationary section. This stationary section is further provided centrally with a socket 25, the purpose of which will presently appear. The rotatable section of the plug comprises two sections 26 and 27, the section 26 forming the body of the rotatable portion of the plug while the section 27 forms the seating section thereof. The body section is provided in its bottom with an annular groove 28 and has axially 80 thereof a threaded aperture 29. Through the side wall of the section 26 is formed a port 30 connecting the outer surface of this side wall with the groove 28, the outer edges of the side wall having downwardly 85 extending portions or lugs 31 entering notches 32 formed in the seating section 27, preventing rotation with relation to the section 26 of the rotatable section of the plug. 90 This seating section is held in position by a retaining element 33 extending therethrough and engaging in the threaded bore 29 of the section 26. The head of this retaining element, indicated at 33, is received within the socket 25 of the stationary section of the plug. The seating section may be formed of fiber, rubber, soft metal or any suitable material and may be replaced as it wears. 95 The rotatable section 20 of the plug is provided with a stem. 100 105 110

In operation, the cover of the cock is a means for forcing the lower surface of the seating section into engagement with the upper surface of the stationary section 19 so as to provide a water tight connection therebetween. The cock plug may be made sufficiently loosely fitting that there is little or no friction between the side wall of the rotating section and the bore 11 and accordingly this body will be relatively easy to turn when the ports 27^a of the section 27 are in alignment with the ports 23, 24 of the stationary section 19. The fluid is led into the groove 28 and passes from this groove through the port 24 to the outlet. The body of the valve is preferably provided with a drain outlet port 35 with which the port 30 aligns when the ports 27^a are out of register with the ports 23, 24 so that this channel may be properly drained at all times.

It will be obvious that the construction hereinbefore set forth may be employed for multiple distribution valves such as are employed in water works or the like by simply providing a plurality of outlet ports 34 in the lower section 19 as suggested in Figure 7. It will also be obvious that while in the present instance, the section 19 is shown as formed separately from the valve bottom and while this is the preferable construction this may also be modified and this section may be produced integrally with the valve body.

Certain other changes and modification being possible without in any manner departing from the spirit of my invention, I accordingly do not limit myself to such specific structure except as hereinafter claimed.

I claim:—

1. In a stop cock, a valve body having a bore and an inlet and an outlet communicating with said bore at one end thereof, a plug including rotating and stationary sections, the stationary section sealing the bore of the body at the end having the inlet and outlet and having ports connecting the inlet and outlet with the upper face of the stationary section, the rotating section having ports opening through its lower face and movable into or out of alignment with the ports of the stationary section and a channel within the rotating section connecting said ports.

2. In a stop cock, a valve body having a bore and an inlet and an outlet communicating with said bore at one end thereof, a plug including rotating and stationary sections, the stationary section sealing the bore of the body at the end having the inlet and outlet and having ports connecting the inlet and outlet with the upper face of the stationary section, the rotating section having ports opening through its lower face and

movable into or out of alignment with the ports of the stationary section, and a channel within the rotating section connecting said ports, said rotating section having a port through its side wall connecting said channel with the outer face of the side wall, said valve body having a bleed port in its side wall with which the last named port of the rotating section aligns when the ports of said rotating section are out of alignment with the ports of the stationary section.

3. In a stop cock, a valve body having a bore and an inlet and an outlet communicating with said bore at one end thereof, a plug including rotating and stationary sections, the stationary section sealing the bore of the body at the end having the inlet and outlet and having ports connecting the inlet and outlet with the upper face of the stationary section, the rotating section having ports opening through its lower face and movable into or out of alignment with the ports of the stationary section, a channel within the rotating section connecting said ports, said rotating section being formed in two parts, one abutting the stationary section and having formed therein the first named ports of the rotating section, the lower part having at its lower face said channel groove and means for securing said parts together.

4. In a stop cock, a valve body having a bore and an inlet and an outlet communicating with said bore at one end thereof, a plug including rotating and stationary sections, the stationary section sealing the bore of the body at the end having the inlet and outlet and having ports connecting the inlet and outlet with the upper face of the stationary section, the rotating section having ports opening through its lower face and movable into or out of alignment with the ports of the stationary section, a channel within the rotating section connecting said ports, said rotating section being formed in two parts, one abutting the stationary section and having formed therein the first named ports of the rotating section, the lower part having at its lower face said channel groove and means for securing said parts together, comprising a headed securing element directed through the first named part and engaging in the second named part, the stationary section of the plug having a socket receiving the head of said securing element.

5. In a stop cock, a valve body having a bore and an inlet and an outlet communicating with said bore at one end thereof, a plug including rotating and stationary sections, the stationary section sealing the bore of the body at the end having the inlet and outlet and having ports connecting the inlet and outlet with the upper face of the stationary section, the rotating section having

- ports opening through its lower face and movable into or out of alignment with the ports of the stationary section, a channel within the rotating section connecting said ports, said rotating section being formed in two parts, one abutting the stationary section and having formed therein the first named ports of the rotating section, the lower part having at its lower face said 10 channel groove and means for securing said parts together, the last named part having lugs engaging the first named part to prevent relative rotation of said parts.
6. A stop cock comprising a valve body having a tapered bore, inlet and outlet ports opening through the lower end of the bore, a rotating tapered plug element mounted within said bore and including a seating section and a body section, the body section having in its lower face an annular groove, the seating section being secured against the lower face of the body section and having 20 ports formed therein alignable with the ports at the bottom of the bore or movable out of alignment with said ports and means limiting the rotation of the plug, the plug and valve body having ports aligning when 25 the ports of the seating section are out of alignment with the ports at the bottom of the bore placing said channel in communication with the exterior of the valve body.
7. A stop cock comprising a valve body having a tapered bore, inlet and outlet ports opening through the lower end of the bore, a rotating tapered plug element mounted 30 within said bore and including a seating section and a body section, the body section having in its lower face an annular groove, the seating section being secured against the lower face of the body section and having 35 ports formed therein alignable with the ports at the bottom of the bore or movable out of alignment with said ports and means limiting the rotation of the plug, the plug and valve body having ports aligning when 40 the ports of the seating section are out of alignment with the ports at the bottom of the bore placing said channel in communication with the exterior of the valve body.

In testimony whereof I hereunto affix my 45
signature.

WILLIAM FRANCIS RYAN.
